AIR HEATER

Thomas W. Torr, Dowagiac, Mich., assignee to
Rudy Furnace Company, Dowagiac, Mich.

Application September 22, 1930
Serial No. 483,484

6 Claims. (Cl. 126—116)

The main objects of this invention are:

First, to provide a highly efficient gas burning air heating furnace.

Second, to provide a gas burning furnace in which the moisture is effectively removed from the products of combustion, permitting the discharge thereof at lower temperatures than otherwise would be practicable.

Third, to provide a structure having these advantages which is quite compact and simple and economical in its parts.

Objects pertaining to details and economies of my invention will definitely appear from the description to follow. The invention is defined in the claims.

A structure which embodies the features of my invention is clearly illustrated in the accompanying drawings in which:

Fig. 1 is a front elevation of an air heating furnace embodying the features of my invention with the casing partially sectioned and broken away.

Fig. 2 is a vertical section on a line corresponding to line 2—2 of Figs. 1 and 3, the smoke or discharge flue being partially broken away.

Fig. 3 is a fragmentary plan view with the casing removed, the discharge flue being shown in section.

Fig. 4 is a vertical section on line 4—4 of Fig. 3 showing details of one of the condenser chambers.

Referring to the drawings, 1 represents a hot air casing or housing having air inlet openings 2 at the bottom and discharges 3 to which the hot air pipes or conduits are connected. Within this housing I arrange heater units designated generally by the numeral 4, which are preferably the units of my application for Letters Patent filed July 13, 1929, Serial No. 378,031.

These units comprise burner chamber portions 5 at the bottom, flue portions 6 at the top and intermediate radiator portions 7. The products of combustion circulate from the combustion or burner chamber 5 through the radiator to the flue chamber 6. The burner 8 is arranged horizontally within the combustion chamber. The combustion chamber is provided with an air inlet 9.

The means for controlling the gas are not illustrated as they form no part of this invention.

Between the heater units I arrange a vertical flat thin-walled condenser chamber 10 and at the sides thereof condenser chambers 11. These condenser chambers are the same in structure except that the chambers 11 are thinner or of less capacity than the chamber 10. These condenser

chambers are preferably thin-walled and formed of sheet material, and, it will be observed, they are arranged in spaced relation to the heater units so that air can circulate freely around the heater units and also around the condenser chambers, which serve or function as heat radiating drums.

These condenser chambers are flat and of substantially the height of the heater units, being connected to the flue portions 6 thereof by means of flues 12 so that the products of combustion circulate from the combustion or burner chamber through the radiator and into the flue chamber 6, from which they pass into the condenser chambers.

The condenser chamber 10 has a discharge flue 13 communicating with the bottom of the stack 14 while the chambers 11 have flues 15 opening to the bottom of this stack.

The condenser chamber is provided with drains 16, the bottoms of the chambers being inclined toward these drains. The drains are preferably located adjacent the discharge flue connections of the condenser chamber.

Inclined baffles 17 are arranged below the inlet connections for the condenser chambers and extend downwardly with their lower ends adjacent to but spaced from the bottoms of the condenser chambers and their walls opposite their discharge flue.

With this arrangement the condensers serve not only to remove the moisture from the products of combustion, permitting its discharge at much lower temperature than would otherwise be practicable, but they also serve as radiating drums so that the structure is highly efficient.

I have illustrated and described my improvements in an embodiment which I have found highly practical. I have not attempted to illustrate or describe other embodiments or adaptations as it is believed that this disclosure will enable those skilled in the art to embody or adapt my improvements as may be desired.

Having thus described my invention what I claim as new and desire to secure by Letters Patent is:

1. In a heater, the combination with a hot air casing, of a plurality of self supporting upright heater units arranged therein and each comprising a burner chamber at the bottom, a flue chamber at the top and an intermediate radiator portion, burners arranged in said burner chambers, vertically disposed flat thin-walled condenser chambers arranged within said casing between and at the outer sides of said heater units

- and in spaced parallel relation thereto to permit the circulation of air around the heater units and condenser chambers, flues connecting all of the flue chambers of said heater units in parallel with the tops of all of said condenser chambers, said condenser chambers being suspended from said flues, interconnected discharge flues connected to the backs of said condenser chambers at the lower ends thereof, inclined baffles arranged within said condenser chambers below the inlet flues, the lower ends of the baffles being disposed adjacent to but spaced from the bottom of the chambers and their walls opposite their discharge flues, and interconnected drain pipes connected to the bottoms near the backs of the chambers, the bottoms of the chambers being inclined toward said drain pipes. 80
- 10 2. In a heater, the combination with a hot air casing, of a plurality of self supporting upright heater units arranged therein and each comprising a burner chamber at the bottom, a flue chamber at the top and an intermediate radiator portion, burners arranged in said burner chambers, vertically disposed flat thin-walled condenser chambers arranged within said casing between and at the outer sides of said heater units and in spaced parallel relation thereto to permit the circulation of air around the heater units and condenser chambers, flues connecting the flue chambers of said heater units in parallel with the tops of said condenser chambers, said condenser chambers being suspended from said flues, interconnected discharge flues connected to said condenser chambers at the lower ends thereof, and drain pipes connected to the bottoms of the chambers. 90
- 15 3. In a heater, the combination with a housing, of a plurality of self supporting upright heater units comprising burner chambers and radiator portions through which the products of combustion are circulated, vertically disposed condenser chambers arranged within said housing between and at the outer sides of said heater units and in spaced parallel relation thereto permitting circulation of air around the heater units and condenser chamber, flues connecting the top of the condenser chamber in parallel with the radiators, a discharge flue connected at the lower end of the condenser chamber, and a drain for said condenser chamber. 95
- 20 4. In a heater, the combination with a housing, of a plurality of heater units comprising burner chambers and radiator portions through which the products of combustion are circulated, a vertically disposed condenser chamber arranged within said housing between said heater units and in spaced parallel relation thereto permitting circulation of air around the heater units and condenser chamber, flues connecting the top of the condenser chamber in parallel with the radiators, a discharge flue connected at the lower end of the condenser chamber, and a drain for said condenser chamber. 100
- 25 5. In a heater, the combination with a housing, of heater units comprising burner chambers and radiator portions through which the products of combustion are circulated, vertically disposed condenser chambers arranged within said housing between and at the outer sides of said heater units and in spaced parallel relation thereto permitting circulation of air around the heater units and condenser chambers, flues connecting the tops of the condenser chambers with the radiators, discharge flues connected at the lower ends of the condenser chambers, and drains for said condenser chambers. 105
- 30 6. In a heater, the combination with a housing, of a plurality of heater units comprising burner chambers and radiator portions through which the products of combustion are circulated, vertically disposed condenser chambers arranged within said housing between and at the outer sides of said heater units and in spaced parallel relation thereto permitting circulation of air around the heater units and condenser chambers, flues connecting the tops of the condenser chambers with the radiators, discharge flues connected at the lower ends of the condenser chambers, and drains for said condenser chambers. 110
